COMBINED DIAL AND HANDS FOR A CLOCK OR SIMILAR ARTICLE

James J. Mover, Swampscott, Mass.

Application December 15, 1955, Serial No. 39,344

Term of patent 14 years

(Cl. D42—1)

FIG. 2

FIG. 1

Figure 1 is a face view of the combined dial and hands for a clock or similar article embodying my invention; and

Figure 2 is a side elevation of the combined dial and hands for a clock or similar article.

The dominant features of the design reside in the portions shown in full lines.

I claim:

The ornamental design for a combined dial and hands for a clock or similar article, as shown and described.
